ATTORNEY

UNITED STATES PATENT OFFICE.

GEORGE MICHALEK, OF MONARCH, WYOMING.

RAIL SUPPORT.

Application filed May 24, 1926. Serial No. 111,085.

This invention relates generally to rails, such as used by railroads of all classes and types, the invention having more particular reference to a novel type of rail support.

5 The invention has for an object the provision of an improved rail support, which may be readily and easily attached to the rail, so as to permit rolling stock to pass over the said rail, and which may be readily and 10 easily removed therefrom in order to effect replacement of the said rail.

For further comprehension of the invention, and of the objects and advantages thereof, reference will be had to the following 15 description and to the accompanying drawing, and to the appended claims in which the various novel features of the invention are more particularly set forth.

Fig. 1, of the drawing, is a perspective 20 view of my improved rail support, as it would appear when in position, so as to support a rail.

Fig. 2, is a side elevational view thereof.

Fig. 3, is a similar view to that shown in 25 Fig. 1, but showing my improved rail support disengaged from the said rail.

Fig. 4, is a similar view to that shown in Fig. 1, but illustrating a modification of my 30 improved rail support.

Fig. 5 shows a face view of a rail gauge.

As here embodied my improved rail support comprises a base 10, rectangular shaped, having preferably tapered sides 11, and provided with extended portions 12, it being 35 understood that the base 10 is adapted to be set in concrete, or the like, and that the said extended portions 12 will project into the said concrete, so as to firmly hold the base 10 in place.

40 The said base 10, is also provided with apertures 13, extending from the top 14, thereof, downward and through the said tapered sides 11, so as to accommodate the rail engaging members 15, which are positioned in the said apertures 14, and are pivotally attached to the said base 10, as at 16, by pins, or any other suitable means. The said engaging members 15, have suitably formed, at 45 their upper extremities jaws 17, having elongated slots 18, adapted to engage the rail 19, at its lower flange 20, when the lower extremities 21, are forced outward, as clearly shown in Fig. 1, of the accompanying drawing, it being understood that the weight of 50 the said rail 19 will hold the rail 19 in en-

gagement with the said rail engaging members 15.

As a means of securely holding the rail 19 in engagement, as above stated, I have provided clips 22, pivotally attached to the said base 10, as at 23, and adapted to engage the notches 24, suitably located in the rail engaging members 15, and clips 25, also pivotally attached to the base 10, as at 26, and adapted to engage the notches 27, suitably 60 located in the lower extremities 21, of the rail engaging members 15.

Referring in particular to Fig. 4, of the accompanying drawing, in which I have illustrated a modification of my improved 65 rail support. As a means of securely holding the rail 19 in engagement, as above stated, I have provided locking members 28, and 29, slidably mounted, as at 30, in the said base 10, and having curved extremities 70 31, adapted to engage notches 32, suitably located in the rail engaging members 15.

Having thus described my invention, what I claim as new and desire to protect by Letters Patent of the United States is as follows:

1. A rail support comprising a base, rail engaging members pivotally attached to the said base provided with jaws adapted to engage a rail, clips pivotally attached to the 85 said base, as a means of securely holding the said rail in engagement.

2. A rail support comprising a base provided with apertures extending from the top of the said base downward and through the 90 sides of the said base, rail engaging members mounted in said apertures pivotally attached to the said base, said rail engaging members having formed at their upper extremities jaws, having elongated slots adapted to engage a rail, at its lower flange, clips pivotally attached to the body of said base, adapted to engage notches located in the said rail engaging members, and in the lower extremities of the said rail engaging members.

3. A rail support comprising a base provided with apertures extending from the top of the said base downward and through the sides of the said base, rail engaging 105 members mounted in said apertures pivotally attached to the said base, said rail engaging members having formed at their upper extremities jaws, having elongated slots adapted to engage a rail, at its lower flange, lock- 110

ing members, slidably mounted in the said base, having curved extremities adapted to engage notches suitably located in the said rail engaging members.

- 5 4. In a device of the class described, a base having tapered sides provided with extended portions, said base provided with apertures extending from the top of the said base, downward and through the said tapered
- 10 sides of the said base, rail engaging members pivotally attached to said base and positioned in the said apertures.

5. In a device of the class described, a base, rail engaging members pivotally mounted in said base, clips pivotally attached to said base adapted to engage notches located in the body of said rail engaging members, and in the lower extremities of the said engaging members, as a means of securely holding a rail in engagement with the said rail engaging members.

In testimony whereof I have affixed my signature.

GEORGE MICHALEK.
